UNITED STATES PATENT OFFICE.

CHARLES W. GRAHAM, OF CRESTWOOD, NEW YORK, ASSIGNOR TO AMERICAN CAN COMPANY, OF NEW YORK, N. Y., A CORPORATION OF NEW JERSEY.

HERMETIC-SEALING DEVICE.

1,351,162.

Specification of Letters Patent. Patented Aug. 31, 1920.

Application filed January 17, 1916. Serial No. 72,600.

To all whom it may concern:

Be it known that I, CHARLES W. GRAHAM, a citizen of the United States, residing at Crestwood, in the county of Westchester 5 and State of New York, have invented certain new and useful Improvements in Hermetic-Sealing Devices, of which the following is a specification.

The invention relates to the hermetic sealing of cans of the so-called sanitary type, without the use of solder for the attachment of the end parts; and has for its objects to improve the perfection of the hermetic joint or seam by which the top end 10 or cover is united to the can body; to simplify the preliminary partial assemblage of the parts; and to make the final sealing operation more simple and free from mistake. To these ends the invention comprises a can body having an outstanding 15 peripheral flange around its mouth, and a packing, such for instance as a paper ring-liner, fixed on said flange so as to be fed with the can body, and to be stationary 20 therewith during the sealing operation, the flange and ring-liner being adapted to be infolded with the cover flange in a known manner to form a hermetic double or equivalent seam. The said flanged can body and 25 packing constitute a sealing element or unit which is or may be supplied to packers for use with any suitable and corresponding top end or cover.

Advantages attendant on this improvement are that a large number or long row 30 of cans being fed to be closed may be inspected at a glance and without waste of time or trouble, to see whether the packing is missing from any can; whereas, when the packings are carried by and fed with the 35 covers they are out of sight and a cover from which the packing has been lost may be attached to a can, with the result that a hermetic joint is not produced. Also it is 40 desirable that the packing be free with respect to the cover and not partake of any 45 rotary movement of the same which may be imparted by the seaming head, but remain fixed with respect to the can flange; whereby 50 the cover may turn smoothly on the packing and the latter will not be abraded, cut or crumpled by being rubbed against either the outer or the inner edge of the can body flange, or against the surface thereof which

is ordinarily not so smooth as the face of 55 the cover.

With such objects in view, as well as other advantages which may be incident to the use of the improvements, the invention consists in the parts and combinations thereof 60 hereinafter set forth and claimed, with the understanding that the several necessary elements constituting the same may be varied in proportions and arrangement without departing from the nature of the invention. 65

In order to make the invention more clearly understood there is shown in the accompanying drawings means for carrying the same into practical effect, without limiting the improvements, in their useful 70 applications, to the particular constructions which, for the purpose of explanation, have been made the subject of illustration. In the said drawings:

Figure 1 is a top plan view of a flanged 75 can body, and a packing, embodying the invention, the cover being indicated in dotted lines.

Fig. 2 is a vertical section of the upper 80 end of the same on a larger scale.

Fig. 3 is a similar view of the sealed can. Referring to the drawings, 1 is the can body formed at its mouth with an outstanding peripheral flange 2. This flange is suitable to be interfolded with a corresponding flange 3 of a top end or can cover 4 in a known manner and by automatic machinery to form a hermetic sanitary closure, with the aid of the interposed packing or ring-liner 5. Such cover is preferably formed with a central depression or shoulder 6 adapted to fit the interior of the can mouth, and with a depending lip or curl 7 at the extremity of the flange 3.

This ring-liner or its equivalent is fixed 95 on the body flange 2 before the body is fed to the closing station. This is done by forming a permanent bend or crimp in the said ring liner or packing so that the ring liner is arranged to partly infold the flange 100 2 and inclose its outer edge. Preferably additional securing by the use of cement between the ring liner and the can body flange is omitted, the said crimping of the ring liner under the can body being ordinarily 105 sufficient to secure the liner as described so that it will not become displaced preliminary to or during the can closing operation.

The described formation of the gasket is a highly practical means for obtaining the described hermetic seal, because, if the outer edge of the paper gasket is not previously 5 folded around the body flange there is no guarantee that it will fold properly around the flange when the double seam is being formed and it would often result that the flange of the body would cut off an outer 10 ring from the paper gasket and squeeze it down into the lower bend of the double seam, which unintended crowding down of the paper has been found to cause ruptures of the metal at various points so as to produce 15 leaks, the cause of which was difficult to determine. In my improved form of seal, if the sharp edge of the body flange should cut off the gasket and separate a portion of it when the double seam is being formed, no 20 harm would result, such as above described, because that portion of the gasket which belongs in the inner fold of the seam is already in position parallel with the under side of the body flange before the seam is 25 started to be formed. My sealing device will therefore make a superior double seam and will always insure that a portion of the paper ring will occupy the said inside fold of the double seam. Thereby two sealed 30 joints are formed, one on the upper or outer face of the can body flange and the other on the under or inner face of the can body flange, which is a desideratum in producing sanitary cans that are reliably hermetically sealed.

What is claimed is:—

1. A means of forming hermetic joints in cans having ends secured thereto by double seams, comprising a can body having an 40 outstanding seaming flange formed on its end, and a can cover having an outstanding seaming flange of greater diameter than

said can body flange, said seaming flange of the cover folding around said body flange and lying parallel with the under surface of 45 said body flange in the completed seam, together with a flat gasket formed with a bent periphery with one leg of the gasket extending under the body flange before the formation of the double seam is begun, so 50 that when a double seam is formed by inter-folding said body and said cover flanges portions of said gasket are in parallel contact with both the inner and outer surfaces of the body flange and the surface of the 55 cover flange is in contact with said parts of the liner to form an hermetic point.

2. A means of forming hermetic joints in cans having ends secured thereto by double seams, comprising a can body having an 60 outstanding seaming flange formed on its end, and a can cover having an outstanding partially turned seaming flange of greater diameter than said can body flange, said partially turned portion folding around 65 said body flange and lying parallel with the undersurface of said body flange in the completed seam, together with a flat gasket placed on the top surface of said body flange and having a peripheral edge extending beyond the edge of said body flange and folded around said edge and having a portion resting against the under surface of said body flange prior to application of the 70 cover thereto so that when a double seam is formed the said gasket forms a filling between the surfaces of said body and cover flanges, tending to close and permanently seal all interstices and irregularities of the 75 surfaces on both sides of said body flange and one side of cover flange and produce thereby an hermetic joint.

In testimony whereof I affix my signature.
CHARLES W. GRAHAM.
